UNITED STATES PATENT OFFICE.

CHARLES L. LILLEBERG, OF CHICAGO, ILLINOIS, ASSIGNOR TO WILLIAM HERBERT JOHNSON, OF CHICAGO, ILLINOIS.

PERFORATING-MACHINE.

1,080,703.

Specification of Letters Patent.

Patented Dec. 9, 1913.

Application filed March 31, 1909, Serial No. 486,916. Renewed July 7, 1911. Serial No. 637,324.

To all whom it may concern:

Be it known that I, CHARLES L. LILLEBERG, citizen of the United States, residing at Chicago, in the county of Cook and State 5 of Illinois, have invented a certain new and useful Improvement in Perforating - Machines, of which the following is a full, clear, concise, and exact description, reference being had to the accompanying drawings, forming a part of this specification.

My invention relates to perforating machines, and is of particular service when adapted to the purpose of cutting music sheets that are to be used in connection 15 with mechanism for playing pianos and organs. I do not wish to be limited, however, to the employment of the machine of my invention for the perforation of paper that is to be used in connection with musical 20 instruments.

In its preferred embodiment, the machine of my invention employs characteristics exhibited in Patent No. 854,822, dated May 28, 1907, issued to Alvin L. Hart, and relating 25 to perforating machines, though it is to be understood that my invention is not to be limited to the type of machines shown in said patent. The machine set forth in said patent includes a roller having annular 30 grooves and a series of cutters adapted to be entered within the grooves, a series of pneumatics, one for operating each cutter, and means whereby a master perforated sheet may govern the operation of said pneumatics so as to govern the operation of said 35 cutters. The cutters coöperate with the grooved roller to form tongues in the sheet to be perforated substantially co-extensive with the length of the aperture to be produced in the sheet, revolving knives being 40 brought into play to cut off these tongues to their bases in completing the perforating operation.

In the device of my invention, I employ 45 two sets of cutters, the cutters of one set partially forming the perforations and the cutters of the other set finishing the perforations, whereby a strip of paper corresponding in length and area to each perforation, will be severed from the paper intact, rather than in comminuted condition, whereby the knives or cutting instruments in the machine of my invention need not be so frequently sharpened.

In the preferred embodiment of my invention, each of the cutters of one set is adapted for very quick operation so as to cut through the paper cross-wise of its travel to form or define one end of the perforation, while each of the cutters of the companion 60 set in its initial movement, is adapted to cut or define the other end of the corresponding perforation and is preferably thereafter continued in operation, preferably by being caused to remain in the position to which it 65 has been actuated, to cut out the strip or piece of paper between the two ends of such perforation. While I prefer to cause the cutters of one set thus to act with extreme speed, in order simply to cut through the 70 paper, and the cutters of the other set to continue in their actuated positions until the desired strips or pieces of paper have been removed, I do not wish to be limited in all 75 embodiments of my invention to the amount of work that the cutters of both sets do relatively.

In carrying out my invention, I desirably employ pneumatic mechanism, in which case I provide two sets of pneumatics, the pneumatics of one set controlling the cutters of one set of cutters and the pneumatics of the other set controlling the cutters of the other set of cutters, there being one pneumatic per cutter. There are two tracker boards 80 over which preferably but one master sheet is caused to pass, said master sheet being perforated and so related to said tracker boards that said tracker boards coöperate 85 with said master sheet to govern the operation of the pneumatics, one tracker board being coöperatively related with the cutters of one set and the other tracker board being co-operatively related with the cutters of the other set.

I will explain my invention more fully by reference to the accompanying drawings, showing a preferred embodiment thereof, in which—

Figure 1 is a plan view of apparatus constructed in accordance with my invention, portions thereof, however, being omitted in order to permit of the illustration of the plan view upon one sheet. Fig. 2 is a sectional elevation of a part of the machine 100 illustrated in Fig. 1. Fig. 3 is a sectional elevation of another part of the machine 105 illustrated in Fig. 1. Fig. 4 is a detail

illustrating a part of the mechanism interposed between a pneumatic and a cutting tool. Fig. 5 is a view in perspective showing the manner in which the cutters may be mounted, part of the structure being shown in section and a part broken away. Figs. 6, 7 and 8 are diagrammatic views illustrating the operation of the apparatus of my invention.

10 Like parts are indicated by similar characters of reference throughout the different figures.

The paper that is to be perforated is taken from a supply roll 1 and after its perforation is wound upon a roll 2, the paper finding its way over suitable tension and guiding rolls 3 in its travel from the roll 1 to the roll 2. The paper that is to be and which has been perforated is indicated by the dotted line 4 (Fig. 2). A revolving roller 5 is provided with annular grooves, into which stationary knives 6 are projected, these knives lying on one side of the path of travel of the paper 4, which rides over the roller 5, these knives 6 presenting cutting edges 7 to said paper, which cutting edges are located at the circumference of the roller 5.

One set of cutters includes knives 8 that are provided with cutting edges 9 adapted, 80 when the knives 8 are actuated, to work in coöperation with the cutting edges 7, whereby the knives 6 possessing said cutting edges 7, act as dies to the knives 8 possessing the cutting edges 9, the portions 7 and 9 acting 85 as shears upon the paper 4. The cutting edges 7 and 9 coöperate to form the transverse cuts that start the perforations or slots in the paper that is to be perforated. The knives 8 are the knives which are desirably 90 maintained in their actuated positions to cut the desired strip or piece of paper from the sheet 4, the knives 6 desirably taking no part in cutting the paper after they have coöperated with the knives 8 to form the 95 transverse cuts in the paper 4. The knives 8 constitute reciprocating knives and, in a broad sense, are governed similarly to the reciprocating knives disclosed in Patent No. 854,822, in that each knife is controlled by 100 a pneumatic 10 having pneumatic connection with a tracker board 11, a single tube 12 being indicated between one pneumatic and the tracker board 11, it being understood that each pneumatic has a tube 12 in 105 connection with the tracker board 11, and that there are as many pneumatics as there are knives and as many apertures in the tracker board 11 as there are tubes 12. The tracker board and pneumatic equipment are 110 so well understood as to require no specific description, it being sufficient to illustrate the preferred form of mechanical connection between the pneumatics and the knives 8 as in Fig. 2.

65 I consider the use of the stationary knives

6 in combination with the movable knives 8 and the grooved roller 5, to be a novel and important departure in apparatus of the class to which my invention relates, for by means thereof the ends of the perforations caused by the knives 8 are well defined and free of burs. The knives 8 constitute one set of cutters which are desirably brought into play to complete the formation of the perforations which are commenced by the knives 13 of another set, the knives 13 preferably serving merely to make transverse cuts in the paper 4, thereby determining where the perforations shall terminate, the knives 8 working toward these cuts, in effect, and ceasing their operation when they reach these cuts, by being withdrawn from the grooves in the roller 5, at which time strips of paper have been removed from the sheet 4, of sizes equal to the perforations that have been produced, these strips of paper being drawn up the flue 14 by pneumatic suction, the fingers of the fender 14' extending into the grooves of the roll 5, and serving to guide the removed strips of paper toward the flue 14. It is, of course, understood that the lengths of these strips or pieces of paper, and therefore the lengths of the perforations, are determined by the periods of time during which the knives 8 are maintained with their cutting noses within the grooves of the roller 5, and that the knives 8 are thus maintained within the grooves of the roller 5 during the time that the slots 15 in the master sheet 16 are in 100 register with the corresponding openings in the tracker board 11, so that perforations are cut in the paper 4 that correspond in length with the perforations in the master sheet 16, whatever the lengths of the perforations in 105 the master sheet may be and no matter how frequently such perforations may occur.

The knives or cutters 13 are governed by the tracker board 17 and the master sheet 16, the tracker board 17 being in pneumatic connection with the pneumatics 18 that serve to operate the knives 13, pneumatic tubes 19 (but one being shown) intervening between the pneumatics 18 and the tracker board 17, whereby the pneumatics 18 are 110 operated just as are the pneumatics 10. Inasmuch as I prefer to permit the knives 13 to operate upon the paper 4 only momentarily, I desirably cause the pneumatics 18 to operate upon the knives 13 indirectly. 115 The pneumatics 18 which remain in actuated positions as long as the slots 15 pass over the corresponding openings in the tracker board 17, are caused to set mechanism that causes the operation of the knives 13, this mechanism being released when the pneumatics 18 are restored to their idle conditions, to effect the operation of the knives 13. The mechanism which is set by the pneumatics 18 desirably includes each a 120 125 130

- spring 20 placed under tension by the associate pneumatic 18 when said pneumatic is actuated, said pneumatic 18, when actuated, setting or shifting the bar 21 to a lower 5 position in which a trip dog 22 carried by the bar 21, may lie below the associate knife or cutter 13 (the cutters 13 being pivoted between their ends, as are the cutters 8), the trip dog being rocked upon its pivot in 10 its downward movement, as a consequence of its engagement with the associate cutter 13, the spring 23 restoring the dog 22 to its normal position with respect to the bar 21 against its stop, when the dog 22 is below 15 the associate knife 13, so that when the pneumatic 18 is released, which occurs when an imperforate portion of the master sheet serves to seal the tracker board opening connected with the pneumatic by the tube 19. 20 The spring 20, no longer under tension by the pneumatic, contracts to elevate the sliding bar 21 and engage the dog 22 with the associate knife 13, the dog 22 escaping said knife 13 after it has sufficiently rocked said 25 knife to cause its cutting edge 24 to pass through the paper 4, the paper 4 passing over a die-plate 25 coöperating with the edges 24 of the knives 13 to produce transverse cuts in the paper 4. It will be seen 30 that the knives 13 operate very sharply and quickly, inasmuch as they are directly operated by the spring 20, the periods of operation being measured by the time that it takes for the springs to contract after they 35 are released by the associate pneumatics 18. I desirably cause the springs 20 merely to force the cutting edges 24 of the knives 13 toward the paper 4, the cutting edges 24 being desirably removed from the paper 4 40 by means of the retractile springs 26 that are permitted to operate as soon as the dogs 22 have escaped the knives 13 upon upward movement of said dogs. Each knife 13 has a pneumatic 18 and the parts that have been 45 described as coöperatively relating the said pneumatic with the knife 13. The spring 23 having a stationary anchorage at one end, serves to prevent the element 33, which may be a thin wire, from buckling, thereby co- 50 operating with the pneumatic 18 when said pneumatic operates to lower the bar 21.
- It will be seen that the spring 20 constitutes a power storage device in which power is stored when the pneumatic is operated. 55 From what has been related, it will be understood that while the knives 8 operate throughout the time that the slots in the master sheet 16 are passing through the corresponding openings in the tracker board 11, the knives 13 are only brought into play when such slots have just cleared the openings in the tracker board 17. In other words, the knives 8 operate as soon as the 60 openings in the tracker board 11 associated therewith have access to the external air 65 through the slots in the master sheet, and are continued in operation during the time the openings or perforations in the master sheet thus uncover the tracker board openings, while, on the other hand, the knives 13 do not operate during the time the openings in the master sheet 16 are in register with the corresponding openings in the tracker board 17, but operate only, and then momentarily, just when the openings or perforations in the master sheet clear the openings in the tracker board 17. It is, of course, understood that the knives 13 may operate at different times with respect to each other, as is the case with the knives 8, each knife being governed by one tracker board opening, such tracker board opening having its control over its associate knife by the perforation or perforations in the master sheet that are traveling in line therewith. 70
- Figs. 6, 7 and 8 illustrate diagrammatically the manner in which a perforation may be formed in the sheet 4. The transverse cut 27 is first formed in the traveling sheet 4 by a knife 13 that is governed in its action indirectly by the perforation 15 in the master sheet 16 and the associate opening 28 in the tracker board 17, in the manner described, the associate knife 13, however, not being operated for reasons which have been explained until the tail end of the aperture 15 has been cleared, the tracker board opening 28 corresponding to such knife. Just as soon as the perforation 15 is in communication with the opening 29, such opening, being thus brought into connection with the external air, causes the operation of the pneumatic in connection therewith, and thereby the operation of the knife 8 associated with said pneumatic, the knife 8 being maintained in its actuated position as long as the perforation 15 is in register with the tracker board opening 29. In Fig. 7 the perforation 15 has just reached the tracker board opening 29, so as to start the other end 30 of the perforation that is to be formed in the product sheet 4 corresponding to the perforation 15 in the master sheet, the cut 30 extending transverse of the sheet 4 and being formed by the knife edges 7 and 9, the longitudinal cuts in the paper 4 employed to form elongated perforations, being formed by the co-operation of the knife edge 9 and the walls of the engaging grooves in the roller 5. In Fig. 8 the perforation 15 is just about to leave said tracker board opening 29, the associate knife 8 being withdrawn from the corresponding annular groove in the roller 5 by the spring associated with it when the pneumatic 10 is released as a consequence of the separation of the perforation 15 from the tracker board opening 29. 75
- It will be apparent by an inspection of the drawings, that no matter what the 80 85 90 95 100 105 110 115 120 125 130

lengths of the apertures 15 may be, nor how close or far apart said apertures are, whether very short or very long, or both very short and very long, apertures of proportional length and similar disposition are formed in the product sheet 4. I provide means for uniformly changing the lengths of the apertures in the product sheet 4, which may be desired particularly where apertures are formed in such sheet very close together. By means of a feature of my invention, I am enabled, for example, to increase the length of each perforation by sixty-fourth of an inch or slightly more or slightly less or as much or as little as may be desired and am also enabled similarly to decrease the lengths of the apertures. It will be understood that the changes in the lengths of the perforations or apertures in the product sheet are similar among all of the perforations. I preferably accomplish the result thus described, by means of the vertically adjustable idler roller 31 adapted to have its bearings moved to varying positions vertically, whereby the extent to which the idler roller 31 may depress the master sheet 16 may be regulated, the roller 31 being located between the tracker boards 11 and 17. By this arrangement, obviously, the effective lengths of the perforations in the master sheet 16 are regulated. If the paper were to be perfectly straight between the tracker boards 11 and 17, the perforations in the sheet 16 would have the greatest effective length, thereby making the perforations in the product sheet 4 uniformly longer. If the roller 31 were permitted to bow or bend the sheet 16 between the tracker boards 11 and 17, then the effective lengths of the perforations in the master sheet 16 would be correspondingly decreased, whereby the perforations in the product sheet 4 would be uniformly shortened.

Presser rollers 32 may be employed to hold the master sheet 16 onto the tracker boards.

As an important detail of construction, I have provided a novel form of connection between the knives and their pneumatics, illustrated in Figs. 2 and 4. The link wires 33 that connect the pneumatics with the knives are engaged each with a pin 34 carried on a part of the cutting mechanism, as the bar 21 or the knife 8. A guard 35 is mounted upon the element which carries the pin 34 and engages the free end of the pin 34, so that the element 33, when in place about the pin, is prevented from becoming dislodged from the pin. When it is desired to separate the elements 33 from the pin 34, the guard 35 may be sprung to one side or swung to one side for the purpose. This feature of my invention is very important, because of the fact that the knives must frequently be replaced as they are so quickly

dulled by the action of the paper thereupon, it being necessary to sharpen such knives quite often.

I use the term "cutter" in the claims, meaning thereby an instrument that is adapted to penetrate the product sheet, as distinguished from that cutter in the Hart patent herein mentioned which comminutes the material of the product sheet after it has been displaced from the product sheet.

While I have herein shown and described one embodiment of my invention and have particularly described details and characteristics of construction, I do not wish to be limited to the embodiment of the invention illustrated, as changes may readily be made without departing from the spirit of the invention.

Having thus described my invention, I claim as new and desire to secure by Letters Patent:—

1. A perforating machine including a cutter for partially forming perforations in a traveling sheet, a power storage device for operating the cutter, mechanism for storing power in said device, a cutter actuating device moved by said mechanism and escaping the cutter when thus moved and moved in a reverse direction by the power storage device when the power storage device is free and then serving to operate and thereafter escape the cutter to permit its return, a second cutter coöperating with the former in forming the perforations, and means for maintaining the second cutter in and bringing it out of action.

2. A perforating machine including a cutter for partially forming perforations in a traveling sheet, a power storage device for operating the cutter, pneumatic mechanism for storing power in said device, a cutter actuating device moved by said pneumatic mechanism and escaping the cutter when thus moved and moved in a reverse direction by the power storage device when the power storage device is free and then serving to operate and thereafter escape the cutter to permit its return, a second cutter coöperating with the former in forming the perforations, pneumatic mechanism for maintaining the second cutter in and bringing it out of action, two tracker boards, one for each pneumatic mechanism, and master sheet material coöperating with the tracker boards to govern the operation of the cutters.

3. A perforating machine including a cutter for cutting a traveling sheet, a power storage device for operating the cutter, pneumatic mechanism for storing power in said device, a cutter actuating device moved by said pneumatic mechanism and escaping the cutter when thus moved and moved in a reverse direction by the power storage device when the power storage device is free and then serving to operate and thereafter

escape the cutter to permit its return, a tracker board for said pneumatic mechanism, and master sheet material coöperating with the tracker board to govern the operation of the cutter.

- 5 4. A perforating machine including a cutter for partially forming perforations in a traveling sheet, a power storage device for operating the cutter, mechanism for storing power in said device, a cutter actuating device moved by said mechanism and escaping the cutter when thus moved and moved in a reverse direction by the power storage device when the power storage device is free and then serving to operate and thereafter escape the cutter to permit its return, a second cutter coöperating with the former in forming the perforations, a roller having an annular groove therein, and means for moving said latter cutter into, maintaining it in and withdrawing it from said groove.
- 10 15 20 25 30 35 40 45 50 55 60 65

5. A perforating machine including a cutter for partially forming perforations in a traveling sheet, a power storage device for operating the cutter, pneumatic mechanism for storing power in said device, a cutter actuating device moved by said pneumatic mechanism and escaping the cutter when thus moved and moved in a reverse direction by the power storage device when the power storage device is free and then serving to operate and thereafter escape the cutter to permit its return, a second cutter coöperating with the former in forming the perforations, a roller having an annular groove therein, pneumatic mechanism moving said latter cutter into, maintaining it in and withdrawing it from said groove, two tracker boards, one for each pneumatic mechanism, and master sheet material coöperating with the tracker boards to govern the operation of the cutters.

6. A perforating machine including a cutter for partially forming perforations in a traveling sheet, pneumatic mechanism for operating said cutter, a second cutter coöperating with the former in forming the perforations, pneumatic mechanism for maintaining the second cutter in and bringing it out of action, two tracker boards, one for each pneumatic mechanism, and master sheet material coöperating with the tracker boards to govern the operation of the cutters.

7. A perforating machine including a cutter for partially forming perforations in a traveling sheet, mechanism for operating said cutter, a second cutter coöperating with the former in forming the perforations, a roller having an annular groove therein, and means for moving said cutter into, maintaining it in and withdrawing it from said groove.

8. A perforating machine including a cutter for partially forming perforations in a traveling sheet, pneumatic mechanism for

operating said cutter, a second cutter coöperating with the former in forming the perforations, a roller having an annular groove therein, pneumatic mechanism for moving said latter cutter into, maintaining it in and withdrawing it from said groove, two tracker boards, one for each pneumatic mechanism, and master sheet material coöperating with the tracker boards to govern the operation of the cutters.

9. A perforating machine including a cutter for partially forming perforations in a traveling sheet, a power storage device for operating the cutter, pneumatic mechanism for storing power in said device, a cutter actuating device moved by said pneumatic mechanism and escaping the cutter when thus moved and moved in a reverse direction by the power storage device when the power storage device is free and then serving to operate and thereafter escape the cutter to permit its return, a second cutter coöperating with the former in forming the perforations, pneumatic mechanism for maintaining the second cutter in and bringing it out of action, two tracker boards, one for each pneumatic mechanism, master sheet material coöperating with the tracker boards to govern the operation of the cutters, and means for changing the physical relation of said sheet material and tracker boards to alter the lengths of the perforations produced in the traveling sheet.

10. A perforating machine including a cutter for partially forming perforations in a traveling sheet, a power storage device for operating the cutter, pneumatic mechanism for storing power in said device, a cutter actuating device moved by said pneumatic mechanism and escaping the cutter when thus moved and moved in a reverse direction by the power storage device when the power storage device is free and then serving to operate and thereafter escape the cutter to permit its return, a second cutter coöperating with the former in forming the perforations, a roller having an annular groove therein, pneumatic mechanism moving said cutter into, maintaining it in and withdrawing it from said groove, two tracker boards, one for each pneumatic mechanism, master sheet material coöperating with the tracker boards to govern the operation of the cutters, and means for changing the physical relation of said sheet material and tracker boards to alter the lengths of the perforations produced in the traveling sheet.

11. A perforating machine including a cutter for partially forming perforations in a traveling sheet, pneumatic mechanism for operating said cutter, a second cutter coöperating with the former in forming the perforations, pneumatic mechanism for maintaining the second cutter in and bringing it out of action, two tracker boards, one for each

- 5 pneumatic mechanism, master sheet material coöperating with the tracker boards to govern the operation of the cutters, and means for changing the physical relation of said sheet material and tracker boards to alter the lengths of the perforations produced in the traveling sheet.
- 10 12. A perforating machine including a cutter for partially forming perforations in a traveling sheet, pneumatic mechanism for operating said cutter, a second cutter coöperating with the former in forming the perforations; a roller having an annular groove therein, pneumatic mechanism for moving said cutter into, maintaining it in and withdrawing it from said groove, two tracker boards, one for each pneumatic mechanism, master sheet material coöperating with the tracker boards to govern the operation of the cutters, and means for changing the physical relation of said sheet material and tracker boards to alter the lengths of the perforations produced in the traveling sheet.
- 15 13. A perforating machine including a cutter for cutting a traveling sheet, a power storage device for operating the cutter, pneumatic mechanism for storing power in said device, a cutter actuating device moved by said pneumatic mechanism and escaping the cutter when thus moved and moved in a reverse direction by the power storage device when the power storage device is free and then serving to operate and thereafter escape the cutter to permit its return, a tracker board for said pneumatic mechanism, master sheet material coöperating with the tracker board to govern the operation of the cutter, and means for causing substantially uniform variations in the lengths of the recesses produced in the traveling sheet.
- 20 14. A perforating machine including a roller having an annular groove therein, an aperture-producing cutter adapted to enter the groove, means for moving said cutter into and out of said groove, thereby to perforate a traveling sheet passed between the cutter and roller, and a cutter within the groove coöperating with the aforesaid cutter to initiate the cutting of apertures in the sheet passing between the former and latter cutters.
- 25 15. A perforating machine including a cutter, mechanism for operating the same, a link connecting said mechanism and cutter, said link engaging a pin carried by the element to be connected with the link, and a movable guard carried by said element and movably overlying the free end of the pin to hold the link in connection with the pin.
- 30 16. A perforating machine including a cutter for partially forming perforations in a traveling sheet, means for actuating said cutter, a second cutter coöperating with the former in forming the perforations, means for actuating the second cutter, and means whereby the relative times of action of said cutters are regulated to produce substantially uniform changes in the perforations produced by the cutters.
- 35 17. A perforating machine including a cutter for partially forming perforations in a traveling sheet, pneumatic means including a tracker board for actuating said cutter, a second cutter coöperating with the former in forming the perforations, pneumatic means including a second tracker board for actuating the second cutter, and means whereby the relative times of action of said cutters are regulated to produce substantially uniform changes in the perforations produced by the cutters.
- 40

In witness whereof, I hereunto subscribe my name this 15th day of March A. D., 1909.
